SECURITY COMMUNICATION SYSTEM

James F. Craib, Great Neck, N. Y., assignor, by
mesne assignments, to Hazeltine Research, Inc.,
Chicago, Ill., a corporation of Illinois

Application April 29, 1942, Serial No. 441,024

31 Claims. (Cl. 179—1.5)

1

The present invention relates to security communication systems and, particularly, to such systems which are especially suitable for the transmission of intelligence in the form of speech signals. In greater particularity, the invention relates to security communication systems of the type in which frequency-component subbands of a speech signal are periodically modified, as by shifting, inverting and interchanging the subbands in the frequency spectrum, thus to modify the intelligibility of the signal when reproduced in conventional manner.

Many systems have heretofore been proposed by which to effect, to a greater or lesser degree, security of communication of speech signals, especially for radio communications which are easily intercepted by unauthorized persons. A security communication system is considered satisfactory from a practical standpoint only when intelligible reproduction of communications by an unauthorized person is practically impossible, even though such person has a complete receiving apparatus capable of rendering the received signals intelligible and lacks only information concerning the preestablished procedure by which the transmission is rendered unintelligible.

It is desirable that a security communication system interrupt and otherwise modify the communication to be transmitted at such a rapid rate as to render the communication so unintelligible that an unauthorized person receiving the communication is unable to understand even syllables of the speech signal when reproduced in conventional manner, or when reproduced merely with frequency-component subbands of the received signal displaced in the frequency spectrum since, where this is possible, the speech signal is in general reproducible as intelligible speech portions against a background of severe noise and a skilled person is frequently able to understand the communication. Further, it is desirable that the rapidity of interruption and modification of the speech signal be so high that intelligibility of the communication cannot be restored without great expenditure of time and effort when accomplished by the method of recording the communication on both sound and visual records, analyzing the visual record to determine the preestablished plan of procedure by which the transmission is rendered unintelligible, and, using this information, reproducing the recorded sound record with completely restored intelligibility of communication. Lastly, it is desirable that the apparatus necessary to effect security of communication be relatively light in weight, compact,

2

inexpensive, and adapted satisfactorily to operate without any adjustments other than the initial adjustments usually made by the manufacturer of the apparatus; that the plan of procedure of rendering the communication unintelligible and of restoring intelligibility be easily, quickly and readily accomplished; and that the band width required to translate the unintelligible signal should not appreciably exceed the band width required to translate the speech signal before it is rendered unintelligible.

It is an object of the present invention, therefore, to provide a new and improved security communication system of the type described and one characterized by a higher degree of security of communication than has heretofore been attainable by known methods and apparatus.

It is a further object of the invention to provide a security communication system particularly suitable for the transmission of speech signals and one in which one or more groups or subbands of the frequency components of the speech signal are interchanged relative to each other, shifted or inverted in the frequency spectrum, or interchanged, shifted and inverted in a predetermined order at intervals not substantially longer than the longest syllabic interval of the speech signal.

It is an additional object of the invention to provide a new and improved security communication system in which the signal to be communicated is rendered unintelligible by modifying the frequency components thereof in accordance with any selected one of a very large number of preestablished plans of procedure which are adapted to be readily and quickly changed from time to time, as desired.

It is an additional object of the invention to provide a new and improved security communication system having any or all of the features specified above as desirable in a system of this nature.

In accordance with one embodiment of the invention, a security communication system comprises an input circuit adapted to have applied thereto a speech signal to be transmitted, the signal comprising frequency components extending over a predetermined frequency band. The system includes means for deriving from the signal a second signal comprising a plurality of frequency-component subbands corresponding to individual portions of the aforesaid frequency band, the frequency-component subbands of the second signal being successively modified relative to each other in a predetermined order at inter-

vals not substantially longer than the longest syllabic interval of the speech signal. The system also includes means for translating and receiving the second signal and for deriving therefrom the speech signal.

In a particular form of the invention, a secrecy communication system of the type described includes a plurality of band-pass filters for separating the speech signal into a plurality of subbands corresponding to individual portions of the speech-signal frequency band, a plurality of modulators individually coupled to the band-pass filters, means for deriving a plurality of displacement carrier waves, means, including electronic switching means, for successively applying the carrier waves individually to the modulators in a predetermined order during intervals not substantially longer than the longest syllabic interval of the speech signal to derive a second signal having modified intelligibility, and an output circuit coupled to the modulators to have applied thereto the second signal, whereby the signal applied to the output circuit is suitable for transmission therefrom to a remote point while maintaining a high degree of secrecy of communication.

For a better understanding of the present invention, together with other and further objects thereof, reference is had to the following description taken in connection with the accompanying drawings, and its scope will be pointed out in the appended claims.

Referring now to the drawings, Fig. 1 is a circuit diagram, partly schematic, of a complete carrier-wave transmitter suitable for use in a secrecy communication system embodying the invention; Fig. 2 comprises graphs representing the manner in which a speech signal may be divided into frequency-component subbands and the manner in which such subbands may be inverted in the frequency spectrum; Fig. 3 is a tabulation illustrating the manner in which the frequency-component subbands of the speech signal may be modified by the arrangement of Fig. 1 to establish secrecy of communication; Fig. 4 is a circuit diagram, partly schematic, of a complete carrier-wave receiver suitable for use in a secrecy communication system embodying the transmitter arrangement of Fig. 1; and Fig. 5 is a circuit diagram of a portion of a secrecy communication system and represents a modified form of displacement carrier-wave generator suitable for use in the transmitter and receiver arrangements of Figs. 1 and 4.

Referring now more particularly to Fig. 1, there is represented, schematically, a complete carrier-wave transmitter suitable for use in a secrecy communication system embodying the invention in a preferred form. The transmitter includes an input circuit, comprising input-circuit terminals 10, 11, adapted to have applied thereto a speech signal to be transmitted. This speech signal has somewhat modified intelligibility and is derived from a speech signal of full intelligibility picked up by a microphone 12 and applied through an audio-frequency amplifier 13, of one or more stages, to an input circuit of a modulator 14, the latter unit having another input circuit to which is coupled a displacement carrier-wave generator 15. The speech signal picked up by the microphone 12 has frequency components extending over a predetermined frequency band, for example from 300 to 3000 cycles, and the speech signal to be transmitted and which is applied to the input-circuit terminals 10, 11, has

the same range of frequency components but comprises the lower modulation sideband of the modulated displacement carrier wave developed in the output circuit of unit 14. That the speech signal to be transmitted has modified intelligibility, as stated, will be evident when it is considered that frequency components of this signal, which correspond to frequency components of the speech signal, are not only inverted with respect thereto in the frequency spectrum but are also shifted upward in the frequency spectrum. For example, frequency components of 300 and 3000 cycles in the speech signal correspond to the respective frequency components of 8700 and 6000 cycles in the speech signal to be transmitted when the generator 15 has a frequency of 9000 cycles. The transmitter includes means for separating the speech signal to be transmitted into a plurality of frequency-component subbands corresponding to individual portions of the frequency band of this signal. This means comprises a plurality of band-pass filters 16, 17 and 18 having their input circuits connected to the output circuit of the modulator 14. Thus, assuming the speech signal to be transmitted has a frequency band from 6000 to 8700 cycles, the band-pass filter 16 may derive, for example, a frequency-component subband corresponding to the portion extending from 8700 to 7800 cycles of the frequency band, the band-pass filter 17 may derive that portion from 7800 to 6900 cycles, and the band-pass filter 18 may derive the portion from 6900 to 6000 cycles.

There is also included in the transmitter a plurality of modulators 19, 20 and 21, each having a signal input circuit, and these input circuits being individually coupled to the output circuits of the band-pass filters 16, 17 and 18. The output circuits of the modulators 19, 20 and 21 are coupled to the input circuit of a low-pass filter 22 through respective amplifiers 23, 24 and 25. The output circuit of the filter 22, in turn, is coupled to the input circuit of a carrier-wave transmitting apparatus 26 which includes a source of carrier waves, a modulator, and one or more stages of radio-frequency amplification. The output circuit of unit 26 is coupled to a radiating antenna system 27, 28.

There is also provided in the transmitter means for deriving a plurality of displacement carrier waves, this means comprising a plurality of carrier-wave generators 29 to 36, inclusive, having respective individual frequencies f_1 to f_8 , inclusive. The frequencies f_1 to f_8 , inclusive, may have the respective values, for example, of 10,800 cycles, 9900 cycles, 7500 cycles, 6600 cycles, 8100 cycles, 4800 cycles, 7200 cycles, and 3900 cycles. There is also included in the transmitter a carrier-wave repeater unit 7 comprising a plurality of repeater devices 37 to 48, inclusive, arranged in groups, for example 37 to 40, inclusive, 41 to 44, inclusive, and 45 to 48, inclusive. Each such group has a common output circuit which is coupled to a carrier-wave input circuit of an individual one of the modulators 19, 20 and 21. Each of the repeater devices 37 to 48, inclusive, has its input electrodes coupled to a given one of the generators 29 to 36, inclusive, and is, in turn, effective to couple the generator, to which it is so coupled, to an associated one of the modulators 19, 20 and 21 when the repeater device is suitably energized and has a suitable bias applied between its input electrodes. The repeater devices 37 to 48, inclusive, are energized from sources of space current, indicated as $+B$, but the input electrodes of each

are normally biased below anode current cutoff from sources of biasing potential indicated as $-C$. At any given instant during the operation of the transmitter of Fig. 1, one repeater device in each of the groups 37 to 40, inclusive, 41 to 44, inclusive, and 45 to 48, inclusive, is biased above cutoff by electronic switching means 49, and the interval during which each tube is so biased is not substantially longer than the longest syllabic interval of the speech signal. The term "syllabic interval" of speech will hereinafter be discussed in greater detail and defined during the description of the operation of the invention. Unit 49 has a plurality of control circuits successively energized at intervals not substantially longer than the longest syllabic interval of the speech signal, each such circuit being coupled to the one of the aforesaid repeater devices of the before-mentioned groups through manually-adjustable switching means 50. The manually-adjustable switching means 50 is provided so that the order of coupling of each of the control circuits of unit 49 to the repeater devices 37 to 48, inclusive, can be established and modified, as desired, from time to time.

The electronic switching means 49 comprises a plurality of identical switching units 51 to 58, inclusive, only the first of which is shown in detailed schematic form. Each of the switching units 51 to 58, inclusive, includes an input circuit, comprising input-circuit terminals 59, 59', and an output circuit comprising output-circuit terminals 60, 61. Each of these units also includes means responsive to a pulse of negative potential applied to the input circuit thereof for developing in the output circuit thereof a pulse of positive potential. This means comprises a pair of vacuum tubes 62, 63, the input electrodes of tube 62 being coupled to the input-circuit terminals 59, 59' and the output electrodes of tube 63 being coupled to the output-circuit terminals 60, 61. The last-named means also comprises means intercoupling the input and output electrodes of the tubes 62, 63 to develop the positive-potential pulse in the output circuit of the unit in response to the application of a negative-potential pulse to the input circuit thereof. The intercoupling means of each of units 51 to 58, inclusive, comprises a voltage divider, comprising serially-connected resistors 64, 65, which couples the output circuit of tube 62 to the input circuit of tube 63 and a time-constant circuit, comprising a condenser 66 and an adjustable grid resistor 67, which couples the output circuit of tube 63 to the input circuit of tube 62. The control circuit of unit 51, which comprises control-circuit terminals 68 and 69, is coupled to the output circuit of tube 63. The electronic switch 49 also includes means for coupling the units 51 to 58, inclusive, in cascade. In order to effect this connection, the output circuit of each unit is coupled to the input circuit of a succeeding unit, the coupling means comprising, in each case, a condenser 68.

There is also included in the electronic switch 49, for a purpose presently to be considered, an additional switching unit 70 comprising an input circuit including input-circuit terminals 71, 71', an output circuit including output-circuit terminals 72, 73, and means responsive to a negative-potential pulse applied to the input circuit for developing a negative-potential pulse in the output circuit. The last-named means comprises a pair of vacuum tubes 74, 75, the output circuit of tube 74 being coupled to the input circuit of tube 75 by a voltage divider, comprising series-con-

nected resistors 76, 77, and the output circuit of tube 75 being coupled to the input circuit of tube 74 by a time-constant circuit comprising a condenser 78 and an adjustable grid resistor 79. The input electrodes of tube 74 are coupled to the input-circuit terminals 71, 71', while the output electrodes of tube 75 are coupled to the output-circuit terminals 72, 73 and the latter terminals are coupled, in turn, to the input-circuit terminals 59, 59' of unit 51 by means of a coupling condenser 69. Thus, units 70 and 51 are similar in circuit arrangement, except that the output-circuit terminals 72, 73 of the former are coupled across the output electrodes of tube 75, whereas the output-circuit terminals 60, 61 of unit 51 are coupled to the cathode circuit impedance of tube 63. The cascade connections of the units of the electronic switch 49 are completed by coupling the output circuit of the last cascaded unit 58 to the input circuit of the additional unit 70 through a coupling condenser 69'.

The manually-adjustable switch 50 includes a plurality of vertical conductive bars 80 to 87, inclusive, which are connected to individual ones of the control circuits of units 51 to 58, inclusive, of the electronic switch 49. The unit 50 also includes a plurality of horizontal conductive bars 88 to 99, inclusive, which are connected to the control electrodes of individual ones of the repeater devices 37 to 48, inclusive. The latter bars may be divided into groups I, II, and III of four bars each to designate, for convenience, the grouping of the bars with relation to the respective groups of repeater devices 37 to 40, inclusive, 41 to 44, inclusive, and 45 to 48, inclusive. Manually-adjustable switch elements are included in unit 50 so that the operator can electrically connect any one of the vertical bars 80 to 87, inclusive, to any one of the horizontal bars 88 to 99, inclusive. These switch elements may comprise a spring-biased contact, not shown for simplicity, which normally would electrically connect each vertical bar to every one of the horizontal bars at their cross-over points. However, only selected ones of the switch elements are permitted to complete the electrical connection between the vertical and horizontal bars. This is accomplished by the insertion of a sheet of insulating material between the switch elements and the vertical or horizontal bars which the switch elements would normally engage, appropriate holes being punched in the sheet of material to form a code card and to permit engagement of only selected vertical elements with their cooperating horizontal bars. The engaging switch elements for one such code card are illustrated in Fig. 1 of the drawings by the solid black circles, and it will be noted that each of the bars 80 to 87, inclusive, is electrically connected to one, and only one, horizontal bar in each of the three groups I, II, and III. Thus, the control circuit of each of units 51 to 58, inclusive, is electrically connected through the manually-adjustable switch 50 to the control electrode of one repeater device in each of the three groups of repeater devices 37 to 40, inclusive, 41 to 44, inclusive, and 45 to 48, inclusive. Preferably, the manually-adjustable switch 50 is constructed with the vertical bars secured on one support member and the horizontal bars secured on another support member, these members being hinged in book-like fashion and one of them supporting the engaging switch elements, a construction which permits ready insertion of the code card between the vertical and horizontal

bars and the switch elements cooperating therewith.

Considering now the operation of the arrangement just described, there is derived by the microphone 12 the speech signal to be transmitted and hereinafter designated as "speech signal X" to distinguish it from the speech signals of modified intelligibility derived therefrom and having frequency components corresponding thereto. The speech signal X is amplified by the audio-frequency amplifier 13, and applied to one input circuit of the modulator 14. There is applied to another input circuit of the modulator 14 a speech-displacement carrier wave generated by the generator 15. There is thus produced in the output circuit of modulator 14 a modulated carrier wave having modulation sidebands, each of which contains frequency components corresponding to the speech signal X. However, these modulation sidebands are each displaced upward in the frequency spectrum from the speech signal X and the frequency components of the lower sideband are inverted with respect to the corresponding frequency components of the speech signal X. Since such frequency-component inversion is useful as a first step in the direction of modification of the intelligibility of the speech signal, the lower sideband alone is selected and utilized in the apparatus which follows the modulator 14 and such sideband thus comprises another speech signal to be transmitted and is hereinafter designated as "speech signal Y." The purpose in using the displacement carrier generator 15 to derive the speech signal Y is primarily to shift the frequency components of the speech signal X to a higher portion of the frequency spectrum where they may be more readily handled for purposes of interchanging, shifting, and inverting them in the frequency spectrum ultimately to derive the unintelligible speech signal to be transmitted.

Assuming, as before, that the displacement carrier generator 15 has a frequency of 9 kilocycles and the speech signal a frequency band from 300 to 3,000 cycles, the modulated displacement carrier wave applied to the input-circuit terminals 10, 11 of the transmitter has a lower sideband extending from 8.7 to 8 kilocycles, comprising the speech signal Y as hereinbefore stated, and an upper sideband extending from 9.3 to 12 kilocycles which is not translated. As previously stated, the band-pass filters 16, 17 and 18 translate only the respective pass bands extending from 8.7 to 7.8 kilocycles, 7.8 to 6.9 kilocycles, and 6.9 to 6.0 kilocycles. Consequently, the band-pass filters 16, 17 and 18 separate the speech signal Y into a plurality of frequency-component subbands corresponding to individual portions of the frequency band of this signal. It may be noted that these subbands correspond to similar subbands into which the speech signal X might be divided. For example, the subbands 8.7-7.8 kilocycles, 7.8-6.9 kilocycles, and 6.9-6.0 kilocycles of the speech signal Y correspond in information content of the signal to be transmitted to the respective subbands .3-1.2 kilocycles, 1.2-2.1 kilocycles, and 2.1-3.0 kilocycles of the speech signal X. The subbands derived by the filters 16, 17 and 18 are individually applied to the signal input circuits of the respective modulators 19, 20 and 21.

Referring now to Fig. 2 of the drawings, the frequency-component subbands derived by the band-pass filters 16, 17 and 18 from the speech signal Y are designated in Fig. 2 as A, B and C,

respectively. It will be noted that each of these subbands is 0.9 kilocycle wide. Further to modify the intelligibility of the speech signal Y, the frequency-component subbands A, B and C are successively modified relative to each other in a predetermined order at intervals not substantially longer than the longest syllabic interval of the speech signal X. This is accomplished by apparatus, presently to be considered, which operates to interchange the position of the subbands, invert the frequency components of individual ones of the subbands, or both interchange the position of the subbands and also invert the frequency components of one or more thereof. Actually, as will presently become apparent, the relative shifting of the subbands A to F, inclusive, does not occur in the frequency band 8.7-6.0 kilocycles, but takes place effectively as though the subbands had first been shifted with relation to each other in this frequency band to derive a signal of modified intelligibility, which may be designated as signal Z, and that thereafter the signal Z had been so shifted in the frequency spectrum that its frequency components occupied the frequency band of .3-3.0 kilocycles. However, for purposes of simplicity in explaining the manner of forming the ultimate signal of modified intelligibility from the subbands A to F, inclusive, the discussion of the next few paragraphs treats the matter as though the relative subband shifting, inverting, and interchanging takes place entirely within the frequency band of 8.7-6.0 kilocycles. This simplified treatment is entirely accurate for purposes of the present discussion.

If the frequency components of the speech signal Y as a whole are inverted while maintaining them in their relative order and within the frequency spectrum of 8.7-6.0 kilocycles, the inverted subbands corresponding to the subbands A, B and C then would occupy the position indicated in Fig. 2 as D, E and F, respectively, in which the subbands appear in their original order. It will be evident, of course, that the ultimate speech signal to be derived, that is, the speech signal having the highest degree of unintelligibility and which is to be transmitted, must include frequency components corresponding to the entire number of frequency components of the speech signal X. This may be effected, for example, by adding the subbands A and C to the inverted subband E or by adding the inverted subbands D and F to the subband B. When the subbands A-F, inclusive, are thus added in all possible arrangements containing the complete original speech frequency components, it can be shown that it is possible to provide 64 arrangements of the subbands while yet transmitting frequency components corresponding to all frequency components of the speech signal X.

However, the transmission of subbands A, B and C in their original position in the frequency band of 8.7-6.0 kilocycles would be intelligible when reproduced by an unauthorized listener if he simply inverted the frequency components of these subbands and shifted them to the corresponding frequency range of .3-3.0 kilocycles of the original speech signal X. This also applied to the inverted subbands D, E and F when used in their original position, except that these subbands need merely be shifted to their corresponding position in the original speech signal X, the inversion step having already been performed on them.

Hence, a higher degree of secrecy may be effected by forming the ultimate signal of modified

intelligibility which is to be transmitted only of frequency-component subbands in which no frequency-component subband, or inverted subband, of the speech signal Y occurs in its normal position with relation to the other two subbands. This reduces the number of possible arrangements of the frequency-component subbands which may be used to form the ultimate signal of modified intelligibility to sixteen. These are tabulated in Fig. 3. Considering specifically one such arrangement of subbands, which is designated in Fig. 3 as code number 1, it will be noted that the subband B has been shifted into that portion of the frequency spectrum normally occupied by subband A, that subband A is shifted to the position normally occupied by subband B, these two subbands thus being merely interchanged, and that subband C has effectively been inverted and shifted in the frequency spectrum to the position which it normally occupies without inversion.

Before considering the precise manner in which the frequency-component subbands are shifted, interchanged relative to each other, inverted, and added to derive the ultimate signal of modified intelligibility, the detailed operation of the electronic switch 49 will first be considered.

In this discussion, frequent reference will be made to the "longest syllabic interval" of the speech signal and it is, therefore, deemed advisable at this point more fully to define the meaning of this term. It has been observed that ordinary speech is effected by word syllables and that the lowest frequency of occurrence of such syllables averages approximately twenty times per second. On this basis, the longest syllabic interval is 50 milliseconds. This, of course, is an average value and in isolated cases the syllabic interval may increase substantially to that of the word interval which, in ordinary speech, has been found to have a value of approximately 700-800 milliseconds as determined by average speech of approximately one-hundred words per minute. Hence, in the present specification and claims, the term "longest syllabic interval" of the speech signal may be defined as an interval of from approximately 50 milliseconds to 700 or 800 milliseconds.

Considering now in detail the operation of the electronic switch 49, the first tube in each of the units 51 to 58, inclusive, and 70, for example tube 62 of unit 51 and tube 74 of unit 70, is normally conductive and thus has relatively high conductance, and the second tube of each of these units is normally nonconductive and hence has low conductance.

Now assume that a negative-potential pulse is applied to the input-circuit terminals 71 and 71' of unit 70. This pulse causes tube 74 to become nonconductive and applies a positive pulse to tube 75 to render the latter conductive. When tube 75 becomes conductive, a negative pulse is applied to the input-circuit terminals 59, 59' of unit 51, thus causing tube 62 of this unit to be nonconductive, thereby to apply a positive pulse to the control electrode of tube 63. There is coupled from the output circuit of unit 51 to the input circuit of unit 62 a positive pulse at the time that tube 63 becomes conductive, but this pulse has no effect on the operation of unit 52, since the first tube of that unit is already in a conductive state. At the same time, a negative pulse is applied from the output circuit of tube 63 through the condenser 66 and the resistor 67 to the control electrode of the first tube 62 of unit 51 and this pulse has a duration, determined by

the time-constant of elements 66 and 67, of approximately 50 milliseconds which corresponds substantially to the longest syllabic interval of the speech signal. At the end of such interval, 5 the amplitude of the last-named pulse decreases to a point at which tube 62 begins once more to be conductive. When this occurs, a negative potential is applied from the output circuit of tube 62 to the control electrode of tube 63 to reduce 10 the conductivity of the latter, the action being rapid and cumulative to render tube 62 fully conductive and tube 63 nonconductive. At this time, a negative pulse is applied from the output circuit of unit 51 to the input circuit of unit 52, thus to 15 render the first tube of the latter unit nonconductive and the second tube of such unit conductive for an interval of approximately 50 milliseconds, as in unit 51.

Consequently, at the end of each such interval, 20 a succeeding one of the units 53 to 58, inclusive, is caused to produce a positive potential pulse in its output circuit. The last unit 58 is arranged to apply a negative pulse to the input circuit of unit 70 at the end of the 50 millisecond interval of operation of the former unit. During the time required for the units 51 to 58, inclusive, to become successively operative, the first tube 74 of unit 70 has been maintained nonconductive by a negative pulse of longer duration, determined by 25 the time-constant of elements 78 and 79, which is applied from the output circuit of tube 75 to the control electrode of tube 74. Tube 74 becomes fully conductive, however, at a time just preceding the time at which the negative potential pulse is applied from unit 58 through the coupling condenser 69' to the input circuit of unit 70. Consequently, unit 70 may be considered a "barrier" unit in that it is not affected by undesired spurious potential pulses applied to its input circuit during the major portion of the interval 30 between the application thereto of desired negative pulses from the output circuit of unit 58. It will thus be evident that the plurality of control circuits of unit 49 are successively energized at intervals not substantially longer than the longest syllabic interval of the speech signal, specifically 50 milliseconds in the example assumed.

As the control circuits of unit 49 are energized successively by the successive operation of units 35 50 to 58, inclusive, positive potential pulses are impressed successively on the vertical bars 80 to 81, inclusive, of the manually-operable switch 60. Thus, when the vertical bar 80 of switch 60 has a positive-potential pulse applied thereto from unit 51, the repeater devices 40, 42 and 48 are biased 40 above cutoff and are conditioned to apply carrier-wave oscillations from the carrier-wave generator 32 to the modulator 19, from the generator 33 to the modulator 20, and from the generator 36 to the modulator 21. Similarly, when the next vertical bar 81 has a positive potential pulse applied thereto from unit 49, the repeater devices 38, 42 and 48 are conditioned to apply carrier-wave oscillations from the respective generators 30, 33 and 36 to the respective modulators 19, 20 and 21.

The carrier waves applied to the modulators 19, 20 and 21 are modulated therein by the frequency-component subbands applied to the modulators from the filters 16, 17 and 18. There is thus 45 developed in the output circuit of each modulator a carrier wave having upper and lower modulation sidebands. As will presently become apparent, only the lower modulation sideband of these modulated carrier waves is used in forming the speech signal of modified intelligibility

to be transmitted. It is desirable that the latter signal occupy a frequency band of the same width as that of the speech signal derived by the microphone 12, for example a band width of 300-3000 cycles, and that it have the same mean frequency as the latter speech signal. This is important not only from the standpoint that the signal of modified intelligibility may readily be translated through conventional audio-frequency translating amplifiers and circuits, but also that it requires minimum band width for the modulated carrier wave which is radiated by the antenna system 27, 28. Assuming that the signal of modified intelligibility is to occupy a frequency band of the same width, and to have the same mean frequency, as that of the speech signal derived by the microphone 12, for example 300-3,000 cycles, the frequency that each of the generators 29 to 36, inclusive, should have is governed by two considerations. First, the lower sideband of the modulated carrier wave developed in the output circuit of each of the modulators 19, 20 and 21 should always lie within the frequency range from 300-3,000 cycles; and, secondly, the frequency components of the lower modulation sideband should correspond to the frequency components of a corresponding one of the subbands A, B and C, or inverted subbands D, E and F, Fig. 2, when the latter subbands are shifted in the frequency spectrum relative to one or more such subbands. To illustrate this by way of example, consider what occurs when the vertical bar 80 of switch 50 is energized with a positive-potential pulse from the electronic switch 49. It has previously been shown that this is effective to couple generators 32, 33 and 36 through the respective repeater devices 40, 42 and 48 to the respective modulators 19, 20 and 21. The lower sideband of the modulated carrier wave developed in the output circuit of modulator 19 includes frequency components in the band of 2.1-1.2 kilocycles in which the frequencies 2.1 and 1.2 kilocycles correspond, respectively, to the frequencies 8.7 and 7.8 kilocycles of the subband A of speech signal Y. Now if the entire speech signal Y were to be shifted into the frequency band of .3-3.0 kilocycles, as by the use of a 5.7 kilocycle carrier wave and the selection of the lower modulation sideband thereof, the subband A would then occupy the portion 3.0-2.1 kilocycles of this frequency band, subband B the portion 2.1-1.2 kilocycles thereof, and subband C the portion 1.2-3 kilocycles thereof. However, this has not been done as only the subband A has been so shifted, but in doing so it will be apparent that the frequency components of the lower sideband of the carrier wave developed in the output circuit of modulator 19, under the actual conditions assumed, correspond to the subband A shifted in the frequency spectrum to the relative position normally occupied by the subband B. The term "relative" position, as here used, refers to the related positions of the subbands as they occur in the speech signal Y. Similarly, the lower sideband of the modulated carrier wave developed in the output circuit of modulator 20 includes frequency components in the band .3-1.2 kilocycles in which the frequencies .3 and 1.2 kilocycles correspond, respectively, to the frequencies 7.8-6.9 kilocycles of the subband B of speech signal Y. The frequency components of this lower sideband thus correspond to the subband B inverted as subband E and shifted into the relative position normally occupied by subband C. Lastly, the lower sideband of the

modulated carrier wave developed in the output circuit of the modulator 21 includes frequency components in the band 3.0-2.1 kilocycles in which the frequencies 3.0 and 2.1 kilocycles correspond, respectively, to the frequencies 6.9 and 6.0 of the subband C of speech signal Y. The frequency components of the latter sideband thus correspond to the subband C shifted to the relative position normally occupied by the subband A. Thus, it will be evident that when these lower modulation sidebands are subsequently selected and added, in a manner presently to be considered, there is derived the ultimate speech signal of modified intelligibility comprising subbands arranged in the manner designated as code No. 7 in the tabulation of Fig. 3. It can similarly be shown that when the vertical bar 81 of switch 50 is energized by unit 49, the subbands E and C are used and occupy the relative positions just described, but the inverted subband D is now used in forming the ultimate speech signal of modified intelligibility and occupies the relative position normally occupied by the subband B. This arrangement of subbands is designated in Fig. 3 as code No. 5.

Since the subbands are interchanged at the end of 50-millisecond intervals as each of the control circuits of the electronic switch 49 becomes successively energized, and in accordance with the particular code card used in unit 50, it is possible to combine the subbands in conformance with the tabulations of Fig. 3 in a very large number of permutations and combinations. It may here be stated that from such possible combinations and permutations, it is possible to use approximately 500,000 different code cards, each of which defines a preconceived plan of operation. Each such code card, of course, will be used for a desired interval of a few minutes, an hour, or a day, but is preferably changed at the end of every few minutes according to a prearranged plan by which a limited number of such code cards, for example 10, could be utilized over a twenty-four hour operating period.

The modulated carrier waves developed in the output circuits of the modulators 19, 20 and 21 are amplified by the respective amplifiers 23, 24 and 25, added in the common output circuit of the latter units, and translated through the low-pass filter 22 which selects the lower sideband of each, as previously stated, to derive a second speech signal having frequency components lying only in the frequency band of .3-3.0 kilocycles as do the frequency components of the original speech signal X, but the second speech signal, unlike the original speech signal, has greatly modified intelligibility. This signal is applied to the modulator of unit 26 to modulate the carrier wave generated therein. There are also applied to the modulator of this unit, simultaneously to modulate the carrier wave thereof, synchronizing potential pulses derived from the output circuit of unit 58. The modulated carrier wave of unit 26 is amplified by the radio-frequency amplifiers of this unit and is applied to the antenna system 27, 28 for radiation therefrom.

From the above description of the transmitter arrangement of Fig. 1, it will be evident that units 7, 19, 20, 21, 22, 29 to 36, inclusive, 49 and 50 comprise means for successively modifying the subbands, derived by the band-pass filters 16, 17 and 18, relative to each other in a predetermined order at intervals not substantially longer than the longest syllabic interval of the speech signal

to derive an ultimate or second signal to be transmitted having its intelligibility modified to a high degree. It will further be evident that this means includes means for deriving a plurality of displacement carrier waves, comprising units 29 to 36, inclusive. It will also be evident that units 7, 49 and 50 comprise means including electronic switching means for successively applying the carrier waves of units 29 to 36, inclusive, individually to the modulators 19, 20 and 21 in a predetermined order during intervals not substantially longer than the longest syllabic interval of the speech signal, thus to derive the speech signal of modified intelligibility to be transmitted.

In connection with the electronic switch 49, it will be seen from the description thereof that this switch comprises a plurality of cascade-connected vacuum tubes 74, 75, 62, 63, etc., the first and alternate ones of the tubes, for example tubes 74, 62, etc., in the cascade arrangement normally having high conductance and the other of the tubes normally having substantially zero conductance. The switch also includes means for coupling the tubes in pairs to cause the tubes successively in pairs to traverse a complete cycle of change of conductance in response to the application of a negative control potential or control signal to the first tube. This means comprises the circuit elements 64, 65, 66, 67 in units 51 to 58, inclusive, elements 76, 77, 78 and 79 in unit 70, and the coupling condensers 69. The electronic switch further includes a plurality of control circuits individually so coupled to the pairs of tubes that each of the control circuits is energized during the change of conductance of one of the tubes of the pair associated therewith, such control circuits comprising control-circuit terminals 61, 68 of the units 51 to 58, inclusive, whereby the control circuits are successively energized. There is additionally included in the electronic switch means for coupling the output circuit of the last of the tubes in the cascade arrangement to the input circuit of the first tube thereof to cause the control circuits to be successively and repeatedly energized, this means comprising the coupling condenser 69.

Fig. 4 is a circuit diagram, partly schematic, of a complete carrier-wave receiver suitable for use with the transmitter arrangement of Fig. 1 in a secrecy communication system embodying the invention. Certain of the elements of this receiver correspond to similar elements of the transmitter arrangement of Fig. 1 and are designated by the same reference numerals primed. The receiver includes means for receiving the signal of modified intelligibility comprising a carrier-wave receiver 110 having an input circuit connected to an antenna ground system 111, 112. The receiver also includes frequency-responsive means for deriving from the received signal frequency-component subbands thereof corresponding to individual portions of the frequency band of the speech signal to be reproduced. This means comprises band-pass filters 113, 114 and 115 corresponding, respectively, to band-pass filters 16, 17 and 18 of the transmitter arrangement but having respective pass bands of 2.1-3.0 kilocycles, 1.2-2.1 kilocycles, and .3-1.2 kilocycles. Each of the band-pass filters has an input circuit which is coupled to the output circuit of the carrier-wave receiver 110 and each includes an output circuit which is coupled to a signal input circuit of an individual one of the modulators 19', 20' and 21'. The output circuits of modu-

lators 19', 20' and 21' are coupled through individual amplifiers 23', 24' and 25' to the input circuit of a band-pass filter 116 having a pass band of 6.0-8.7 kilocycles. The output circuit of unit 116 is coupled to an input circuit of a modulator 14', the latter having an additional input circuit to which is coupled a carrier-wave generator 15'. The output circuit of modulator 14' is coupled through a low-pass filter 117 having a pass band of 300-3,000 cycles, to the input circuit of an audio-frequency amplifier 118, and there is coupled to the output circuit of the latter unit a suitable reproducing device comprising a loud-speaker 119.

As in the transmitter arrangement of Fig. 1, there are coupled to carrier-wave input circuits of the modulators 19', 20' and 21' a carrier-wave repeater unit 7'. The carrier-wave receiver 110 includes means for separating the synchronizing-signal components of the received carrier wave, and these components are applied to the input circuit including input-circuit terminal 71' of electronic switch 49', there being the difference in the electronic switch 49' of the receiver that the output of the last unit thereof is not coupled to the input circuit of the additional unit, as in the electronic switch 49 of the transmitter arrangement. This arrangement insures operation of unit 49' only in synchronism with unit 49 of the transmitter. The control circuits of the electronic switch 49' are coupled to the vertical bars of the manually-operable switch 50' and the horizontal bars thereof are coupled to the input electrodes of the relay devices of unit 7' as at the transmitter. Also coupled to the input electrodes of the repeater devices of unit 7' are a plurality of displacement carrier generators 29' to 36', inclusive, in the same manner as at the transmitter.

Considering now the operation of the receiver arrangement just described, the carrier wave radiated by the transmitter is received by the carrier-wave receiver 110 and the modulation components thereof, comprising the signal of modified intelligibility, are derived in unit 110 and applied to the band-pass filters 113, 114 and 115. The latter units derive the frequency-component subbands of the signal of modified intelligibility and apply these subbands to the respective modulators 19', 20' and 21'. The synchronizing-signal components of the received carrier wave are applied to the input circuit, comprising input-circuit terminal 71' of the electronic switch 49', in order that the control circuits of this unit may be successively energized in synchronized relation with those of the corresponding electronic switch of the transmitter. As at the transmitter, the electronic switch 49' successively energizes groups of the relay devices of unit 7' in accordance with the plan of transmission determined by the manually-operable switch 50', and the relay devices, upon being thus energized, operate to apply such of the carrier waves of units 29' to 36' as are necessary successively to interchange the frequency-component subbands derived by units 113, 114 and 115 relative to each other at intervals corresponding to the intervals at which these subbands were interchanged at the transmitter, but in reverse order to that at the transmitter, thus to derive in the output circuits of modulators 19', 20' and 21' modulated carrier waves, one modulation sideband of each of which corresponds to a particular frequency-component subband of the speech signal Y at the transmitter installation. These derived sub-

bands are amplified by amplifiers 23', 24' and 25' and applied to a speech-signal input circuit of the band-pass filter 116 which selects the proper sidebands and applies them to an input circuit of modulator 14'. There is also applied to a carrier-wave input circuit of the latter unit a carrier wave generated by the carrier-wave generator 15', thereby to provide a modulated carrier wave, the lower sideband of which lies in the frequency band of .3-3.0 kilocycles and corresponds to the speech signal to be reproduced, which, of course, is the speech signal X of full intelligibility derived by the microphone 12 of the transmitter. This sideband is selected by low-pass filter 117 and applied to the audio-frequency amplifier 118 where it is amplified and the amplified signal is then applied to the reproducing device 119 for reproduction in conventional manner.

From the above description of the receiver arrangement of Fig. 4, it will be evident that units 7', 14', 15', 19', 20', 21', 29' to 36', inclusive, 49', 50', 116 and 117 comprise means for successively modifying the frequency-component subbands derived by the band-pass filters 113, 114 and 115 relative to each other at intervals corresponding to the intervals at which the subbands were interchanged at the transmitter, but in reverse order to the predetermined order of modification at the transmitter, and for adding the modified subbands to derive the speech signal to be reproduced. It will further be evident that this means includes electronic switching means and also includes the means for deriving the plurality of displacement carrier waves comprising units 29' and 36'.

Fig. 5 represents a modified form of means for deriving the plurality of displacement carrier waves, this modified form being suitable for use either or both at the transmitter and receiver installations. The arrangement of Fig. 5 includes a carrier-wave generator 120 for generating a carrier wave having a fundamental frequency and a wide band of harmonic frequencies. The output circuit of the generator 120 is coupled to the input circuits of a plurality of sharply-tuned band-pass filters 121 to 127, inclusive, each of which selects and translates only the fundamental frequency or a desired harmonic-frequency component of the carrier wave generated by unit 120. The output circuit of each of the band-pass filters 121 to 126, inclusive, is coupled to the input electrodes of the repeater devices of unit 7 in the same manner as the carrier-wave generators 29 to 36, inclusive, of the Fig. 1 arrangement. There is the difference in the present arrangement over the use of the carrier-wave generators 29 to 36, inclusive, of Fig. 1, that since the carrier waves translated by the band-pass filters 121 to 126, inclusive, are harmonically related, it can be demonstrated that fewer carrier waves are required in the Fig. 5 arrangement than in that of Fig. 1, since a greater number of the repeater devices in unit 7 may properly be coupled to the output circuit of certain ones of the band-pass filters 121 to 126, inclusive, in effecting the derivation of the ultimate speech signal of modified intelligibility. The output of the band-pass filter 127 comprises the fundamental-frequency component of the carrier wave generated by unit 120 and thus is used as a synchronizing signal which is applied to the modulator of unit 28 of the transmitter to be transmitted simultaneously with the required synchronizing signal for the electronic switches 49 and 49'.

When the arrangement of Fig. 5 is used at the receiver, unit 127 is dispensed with and the synchronizing-signal component of the received carrier wave is applied to a synchronizing circuit of the carrier-wave generator 120 in conventional manner to synchronize its operation with the corresponding unit of the transmitter apparatus. The operation of the Fig. 5 arrangement is otherwise essentially similar to that described above in connection with Fig. 1 and will not be repeated.

As illustrative of specific frequency values suitable for use with the modified form of displacement carrier-wave generating means of the type shown in Fig. 5, the following values may be used:

	Kilocycles
Frequency of carrier-wave generator 120	2
Mean frequency of the pass band of filter 121	22
Mean frequency of the pass band of filter 122	20
Mean frequency of the pass band of filter 123	16
Mean frequency of the pass band of filter 124	14
Mean frequency of the pass band of filter 125	10
Mean frequency of the pass band of filter 126	8
Mean frequency of the pass band of filter 127	2

From the above description of the invention, it will be evident that a secrecy communication system embodying the invention provides an exceptionally high degree of unintelligibility of the transmitted speech signal. The unintelligibility of the signal is due largely to two factors. The first of these concerns the particular manner, heretofore described, of interchanging and inverting the frequency-component subbands of the speech signal. The second factor concerns the rate of interruption of the speech signal; that is, the rate at which the frequency-component subbands are interchanged and inverted relative to each other. In the arrangement hereinbefore described, such interruption occurs at 50 millisecond intervals, which is equivalent to a rate of interruption of twenty times per second. This rate of interruption is one which has been found by actual operation to be quite satisfactory from the standpoint of rendering the transmitted speech signal highly unintelligible. The lower limit at which the rate of interruption is reasonably effective is perhaps of the order of the average word interval which, as has previously been pointed out, is approximately one hundred times per minute or an interruption interval of approximately 700 to 800 milliseconds. In connection with the upper limit at which the rate of interruption is reasonably effective, it has been stated by some research workers in this field that there are several bands of interruption rate at which the speech becomes in large part unintelligible with intervening bands of interruption rate at which the intelligibility of the speech is found to be satisfactory, that an upper limit of interruption rate occurs at approximately 2,000 times per second, and that above this limit the intelligibility of the speech is no longer impaired by interruption.

While the invention has been described as embodied in an arrangement wherein the ultimate signal of modified intelligibility has frequency components in the frequency band of .3-3.0 kilo-

cycles, it will be evident that the frequency-component subbands A to F, inclusive, of the speech signal Y may, by proper choice of the carrier-wave generators 29-36, inclusive, be so shifted with relation to each other that the ultimate signal of modified intelligibility may have frequency components which occupy any desired band of frequencies located in any desired portion of the frequency spectrum.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A secrecy communication system comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other in a predetermined order at intervals not substantially longer than the longest syllabic interval of said speech signal, and means for translating and receiving said second signal and for deriving therefrom said first-named signal.

2. A secrecy communication system comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively shifted relative to each other in a predetermined order at intervals not substantially longer than the longest syllabic interval of said speech signal, and means for translating and receiving said second signal and for deriving therefrom said first-named signal.

3. A secrecy communication system comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other and the frequency components of at least one such subband being inverted in the frequency spectrum in a predetermined order at intervals not substantially longer than the longest syllabic interval of said speech signal, and means for translating and receiving said second signal and for deriving therefrom said first-named signal.

4. A secrecy communication system comprising, an input circuit adapted to have applied thereto a speech signal to be transmitted, said signal comprising frequency components extending over a predetermined frequency band, means for deriving from said signal a second signal com-

5

prising a plurality of frequency-component subbands corresponding to individual portions of said frequency band, the frequency-component subbands of said second signal being successively modified relative to each other and the frequency components of at least one of such subbands being shifted in the frequency spectrum in a predetermined order at intervals not substantially longer than the longest syllabic interval of said speech signal, and means for translating and receiving said second signal and for deriving therefrom said first-named signal.

10

5. A secrecy communication system comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other and the frequency components of at least one of such subbands being inverted and of at least another of said subbands being shifted in the frequency spectrum in a predetermined order at intervals not substantially longer than the longest syllabic interval of said speech signal, and means for translating and receiving said second signal and for deriving therefrom said first-named signal.

30

6. A secrecy communication system comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other and the frequency components of at least one of such subbands being inverted and shifted in the frequency spectrum in a predetermined order at intervals not substantially longer than the longest syllabic interval of said speech signal, and means for translating and receiving said second signal and for deriving therefrom said first-named signal.

40

7. A secrecy communication system comprising, an input circuit adapted to have applied thereto a speech signal to be transmitted, said signal comprising frequency components extending over a predetermined frequency band, electronic switching means for deriving from said signal a second signal comprising a plurality of frequency-component subbands corresponding to individual portions of said frequency band, the frequency-component subbands of said second signal being successively modified relative to each other in a predetermined order at intervals not substantially longer than the longest syllabic interval of said speech signal, and means for translating and receiving said second signal and for deriving therefrom said first-named signal.

50

8. A secrecy communication system comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively

modified relative to each other in a predetermined order at intervals of substantially fifty milliseconds duration, and means for translating and receiving said second signal and for deriving therefrom said first-named signal.

9. A secrecy communication system comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other in a predetermined order at intervals not substantially longer than the longest syllabic interval of said speech signal, manually-adjustable switch means for establishing and modifying as desired from time to time the said predetermined order of interchanging of said frequency-component subbands, and means for translating and receiving said second signal and for deriving therefrom said first-named signal.

10. A secrecy communication transmitter comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other in a predetermined order at intervals not substantially longer than the longest syllabic interval of said speech signal, and an output circuit coupled to said means to have applied thereto said second signal, whereby the signal applied to said output circuit has modified intelligibility and is suitable for transmission therefrom to a remote point while maintaining a high degree of secrecy of communication.

11. A secrecy communication transmitter comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other and the frequency components of at least one of such subbands being inverted in the frequency spectrum in a predetermined order at intervals not substantially longer than the longest syllabic interval of said speech signal, and an output circuit coupled to said means to have applied thereto said second signal, whereby the signal applied to said output circuit has modified intelligibility and is suitable for transmission therefrom to a remote point while maintaining a high degree of secrecy of communication.

12. A secrecy communication transmitter comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of

said frequency band, the frequency-component subbands of said second signal being successively modified relative to each other and the frequency components of at least one of such subbands being shifted in the frequency spectrum in a predetermined order at intervals not substantially longer than the longest syllabic interval of said speech signal, and an output circuit coupled to said means to have applied thereto said second signal, whereby the signal applied to said output circuit has modified intelligibility and is suitable for transmission therefrom to a remote point while maintaining a high degree of secrecy of communication.

13. A secrecy communication transmitter comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other and the frequency components of at least one of such subbands being inverted and of at least another of such subbands being shifted in the frequency spectrum in a predetermined order at intervals not substantially longer than the longest syllabic interval of said speech signal, and an output circuit coupled to said means to have applied thereto said second signal, whereby the signal applied to said output circuit has modified intelligibility and is suitable for transmission therefrom to a remote point while maintaining a high degree of secrecy of communication.

14. A secrecy communication transmitter comprising, an input circuit adapted to have applied thereto a speech signal to be transmitted, said signal comprising frequency components extending over a predetermined frequency band, electronic switching means for deriving from said signal a second signal comprising a plurality of frequency-component subbands corresponding to individual portions of said frequency band, the frequency-component subbands of said second signal being successively modified relative to each other in a predetermined order at intervals not substantially longer than the longest syllabic interval of said speech signal, and an output circuit coupled to said means to have applied thereto said second signal, whereby the signal applied to said output circuit has modified intelligibility and is suitable for transmission therefrom to a remote point while maintaining a high degree of secrecy of communication.

15. A secrecy communication transmitter comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other in a predetermined order at intervals of substantially fifty milliseconds duration, and an output circuit coupled to said means to have applied thereto said second signal, whereby the signal applied to said output circuit has modified intelligibility and is suitable for transmission therefrom to a remote

point while maintaining a high degree of secrecy of communication.

16. A secrecy communication transmitter comprising, an input circuit adapted to have applied thereto a speech signal to be transmitted, said signal comprising frequency components extending over a predetermined frequency band, means for deriving from said signal a second signal comprising a plurality of frequency-component subbands corresponding to individual portions of said frequency band, the frequency-component subbands of said second signal being successively modified relative to each other in a predetermined order at intervals not substantially longer than the longest syllabic interval of said speech signal, manually-adjustable switch means for establishing and modifying as desired from time to time the said predetermined order of interchanging of said frequency-component subbands, and an output circuit coupled to said means to have applied thereto said second signal, whereby the signal applied to said output circuit has modified intelligibility and is suitable for transmission therefrom to a remote point while maintaining a high degree of secrecy of communication.

17. A secrecy communication transmitter comprising, an input circuit adapted to have applied thereto a speech signal to be transmitted, said signal comprising frequency components extending over a predetermined frequency band, means for separating said speech signal into a plurality of frequency-component subbands corresponding to individual portions of said frequency band, means for successively modifying said subbands relative to each other in a predetermined order at intervals not substantially longer than the longest syllabic interval of said speech signal to derive a second signal having modified intelligibility, an output circuit coupled to said last-named means to have applied thereto said second signal, whereby the signal applied to said output circuit is suitable for transmission therefrom to a remote point while maintaining a high degree of secrecy of communication.

18. A secrecy communication transmitter comprising, an input circuit adapted to have applied thereto a speech signal to be transmitted, said signal comprising frequency components extending over a predetermined frequency band, means for separating said speech signal into a plurality of frequency-component subbands corresponding to individual portions of said frequency band, means for deriving a plurality of displacement carrier waves, means including said last-named means for successively modifying said subbands relative to each other in a predetermined order at intervals not substantially longer than the longest syllabic interval of said speech signal to derive a second signal having modified intelligibility, and an output circuit coupled to said last-named means to have applied thereto said second signal, whereby the signal applied to said output circuit is suitable for transmission therefrom to a remote point while maintaining a high degree of secrecy of communication.

19. A secrecy communication transmitter comprising, an input circuit adapted to have applied thereto a speech signal to be transmitted, said signal comprising frequency components extending over a predetermined frequency band, a plurality of band-pass filters for separating said speech signal into a plurality of subbands corresponding to individual portions of said frequency band, a plurality of modulators individually coupled to said band-pass filters, means for deriving

a plurality of displacement carrier waves, means including electronic switching means for successively applying said carrier waves individually to said modulators in a predetermined order during intervals not substantially longer than the longest syllabic interval of said speech signal to derive a second signal having modified intelligibility, and an output circuit coupled to said modulators to have applied thereto said second signal, whereby the signal applied to said output circuit is suitable for transmission therefrom to a remote point while maintaining a high degree of secrecy of communication.

20. A secrecy communication transmitter comprising, an input circuit adapted to have applied thereto a speech signal to be transmitted, said signal comprising frequency components extending over a predetermined frequency band, a plurality of band-pass filters for separating said speech signal into a plurality of frequency-component subbands corresponding to individual portions of said frequency band, a plurality of modulators individually coupled to said filters, means for deriving a plurality of displacement carrier waves, a plurality of repeater devices arranged in groups each adapted to apply a predetermined group of said carrier waves to individual ones of said modulators, electronic switching means having a plurality of control circuits successively energized at intervals not substantially longer than the longest syllabic interval of said speech signal, each of said control circuits being coupled to one repeater device in each of said groups of repeater devices and when energized being effective to render said one repeater device operative to apply a group of said carrier waves to individual ones of said modulators, thereby successively to modify said frequency-component subbands relative to each other at said intervals, and an output circuit coupled to all of said modulators for combining the interchanged frequency-component subbands to derive a second signal having modified intelligibility, whereby the signal derived in said output circuit is suitable for transmission therefrom to a remote point while maintaining a high degree of secrecy of communication.

21. A secrecy communication transmitter comprising, an input circuit adapted to have applied thereto a speech signal to be transmitted, said signal comprising frequency components extending over a predetermined frequency band, a plurality of band-pass filters for separating said speech signal into a plurality of frequency-component subbands corresponding to individual portions of said frequency band, a plurality of modulators individually coupled to said filters, means for deriving a plurality of displacement carrier waves, a plurality of repeater devices arranged in groups each adapted to apply a predetermined group of said carrier waves to individual ones of said modulators, electronic switching means having a plurality of control circuits successively energized at intervals not substantially longer than the longest syllabic interval of said speech signal, each of said control circuits being coupled to one repeater device in each of said groups of repeater devices and when energized being effective to render said one repeater device operative to apply a group of said carrier waves to individual ones of said modulators, thereby successively to modify said frequency-component subbands relative to each other at said intervals, manually-adjustable switching means for establishing and modifying as desired from time to

time the order of coupling of each of said control circuits to said repeater devices, and an output circuit coupled to all of said modulators for combining the interchanged frequency-component subbands to derive a second signal having modified intelligibility, whereby the signal derived in said output circuit is suitable for transmission therefrom to a remote point while maintaining a high degree of secrecy of communication.

22. A secrecy communication receiver comprising, means for receiving a signal of modified intelligibility which is derived from a speech signal to be reproduced and which includes frequency-component subbands corresponding to individual portions of the frequency band of said speech signal but having said subbands successively modified relative to each other in a predetermined order at intervals not substantially longer than the longest syllabic interval of said speech signal, frequency-responsive means for deriving said frequency-component subbands of said received signal, and means for successively modifying said derived frequency-component subbands relative to each other at intervals corresponding to said first-named intervals but in reverse order to said predetermined order and for adding said last-named modified subbands to derive said signal to be reproduced.

23. A secrecy communication receiver comprising, means for receiving a signal of modified intelligibility which is derived from a speech signal to be reproduced and which includes frequency-component subbands corresponding to individual portions of the frequency band of said speech signal but having said subbands successively modified relative to each other in a predetermined order at intervals not substantially longer than the longest syllabic interval of said speech signal, frequency-responsive means for deriving said frequency-component subbands of said received signal, and electronic switching means for successively modifying said derived frequency-component subbands relative to each other at intervals corresponding to said first-named intervals but in reverse order to said predetermined order and for adding said last-named modified subbands to derive said signal to be reproduced.

24. A secrecy communication receiver comprising, means for receiving a signal of modified intelligibility which is derived from a speech signal to be reproduced and which includes frequency-component subbands corresponding to individual portions of the frequency band of said speech signal but having said subbands successively modified relative to each other in a predetermined order at intervals not substantially longer than the longest syllabic interval of said speech signal, frequency-responsive means for deriving said frequency-component subbands of said received signal, means for deriving a plurality of displacement carrier waves, and means including said last-named means for successively modifying said derived frequency-component subbands relative to each other at intervals corresponding to said first-named intervals but in reverse order to said predetermined order and for adding said last-named modified subbands to derive said signal to be reproduced.

25. A secrecy communication receiver comprising, means for receiving a signal of modified intelligibility which is derived from a speech signal to be reproduced and which includes frequency-component subbands corresponding to individual portions of the frequency band of said speech signal but having said subbands successively modified relative to each other in a predetermined order at intervals not substantially longer than the longest syllabic interval of said speech signal, frequency-responsive means for deriving said frequency-component subbands of said received signal, and electronic switching means for successively modifying said derived frequency-component subbands relative to each other at intervals corresponding to said first-named intervals but in reverse order to said predetermined order and for adding said last-named modified subbands to derive said signal to be reproduced.

fied relative to each other in a predetermined order at intervals not substantially longer than the longest syllabic interval of said speech signal, a plurality of band-pass filters for deriving said frequency-component subbands of said received signal, a plurality of modulators individually coupled to said filters, means for deriving a plurality of displacement carrier waves, and means including electronic switching means for successively applying said carrier waves individually to said modulators in a predetermined order during intervals corresponding to said first-named intervals successively to modify said derived frequency-component subbands in reverse order to said predetermined order and for adding the outputs of said modulators to derive said signal to be reproduced.

26. An electronic switch comprising, a plurality of cascade-connected vacuum tubes, means intercoupling said tubes in pairs to cause said tubes successively in pairs to traverse a complete cycle of change of conductance in response to the application of a control signal to the first of said cascaded tubes, and a plurality of control circuits individually so coupled to said pairs of tubes that each of said control circuits is energized during the change of conductance of one of the tubes of the pair associated therewith, whereby said control circuits are successively energized.

27. An electronic switch comprising, a plurality of cascade-connected vacuum tubes, alternate ones of said tubes in the cascade arrangement normally having high conductance and the other of said tubes normally having low conductance, means intercoupling said tubes in pairs to cause said tubes successively in pairs to traverse a complete cycle of change of conductance in response to the application of a control signal to the first of said cascaded tubes, and a plurality of control circuits individually so coupled to said pairs of tubes that each of said control circuits is energized during the change of conductance of one of the tubes of the pair associated therewith, whereby said control circuits are successively energized.

28. An electronic switch comprising, a plurality of cascade-connected vacuum tubes, a first and alternate ones of said tubes in the cascade arrangement normally having high conductance and the other of said tubes normally having low conductance, means intercoupling said tubes in pairs with a normally high conductance tube as the first tube of each pair to cause said tubes successively in pairs to traverse a complete cycle of change of conductance in response to the application of a control signal to the first of said cascade tubes, and a plurality of control circuits individually so coupled to said pairs of tubes that each of said control circuits is energized during the change of conductance of one of the tubes of the pair associated therewith, whereby said control circuits are successively energized.

29. An electronic switch comprising, a plurality of cascade-connected vacuum tubes, means intercoupling said tubes in pairs to cause said tubes successively in pairs and at the ends of predetermined equal time intervals to traverse a complete cycle of change of conductance in response to the application of a control signal to the first of said cascade tubes, and a plurality of control circuits individually so coupled to said pairs of tubes that each of said control circuits is energized during the change of conductance of one of the tubes of the pair associated therewith, whereby said control circuits are successively energized.

30. An electronic switch comprising, a plurality of cascade-connected vacuum tubes, means intercoupling said tubes in pairs to cause said tubes successively in pairs to traverse a complete cycle of change of conductance in response to the application of a control signal to the first of said cascaded tubes, a plurality of control circuits individually so coupled to said pairs of tubes that each of said control circuits is energized during the change of conductance of one of the tubes of the pair associated therewith, and means coupling the output circuit of the last of said cascade tubes to the input circuit of the first tube thereof, whereby said control circuits are successively and repeatedly energized.

31. An electronic switch comprising, a plurality of cascade-connected vacuum tubes, the first and

alternate ones of said tubes in the cascade arrangement normally having high conductance and the other of said tubes normally having low conductance, means intercoupling said tubes in pairs with a normally high conductance tube as the first tube of each pair to cause said tubes successively in pairs to traverse a complete cycle of change in conductance in response to the application of a negative potential pulse to the first of said cascade tubes, and a plurality of control circuits individually so coupled to said pairs of tubes that each of said control circuits is energized during the change of conductance of one of the tubes of the pair associated therewith, whereby said control circuits are successively energized.

JAMES F. CRAIB.
